IRONER

Adolph A. Myers and Edgar W. Archer,
Louisville, Ky.

Application January 18, 1930. Serial No. 421,803

8 Claims. (Cl. 223—17)

Our invention relates to garment drying apparatus, and particularly to one which is especially adapted for drying or ironing hosiery.

Briefly stated, the invention has for one of its primary objects to provide a drying or ironing device incorporating a body portion which is adjustable to fit different sized garments.

Another object of the invention is to furnish a device of this kind having an adjustable body portion, means for adjusting the body portion, and means for holding the body portion in a predetermined adjusted position.

A further object of the invention resides in the provision of a device for the purpose specified having a body portion provided with an extensible portion and extensible supply and return conduits for a heating medium.

A still further object of the invention is to provide a device of the character mentioned which will be relatively simple in construction, easy to assemble, and highly efficient in practical use.

The invention also resides in certain novel features of construction, combination and arrangement of the various parts and in modes of operation, all of which will be readily apparent to those skilled in the art upon reference to the accompanying drawings in connection with the detailed description appearing hereinafter.

30 The drawings illustrate what now appears to be a preferred embodiment of the invention but it is to be understood that the same is capable of other mechanical expressions within the spirit and scope of the subject matter claimed hereinafter.

In the drawings,

Figure 1 is a central vertical sectional view illustrating a hosiery dryer or ironer embodying our invention and showing the toe portion of the body extended;

Figure 2 is an enlarged detail view of the extensible toe portion of the body;

Figure 3 is a detailed side elevational view of a fragment of the body taken at right angles to Figure 1;

Figure 4 is a sectional view taken on the line 4—4 of Figure 1;

Figure 5 is a sectional view taken on the line 5—5 of Figure 2;

50 Figure 6 is a fragmentary longitudinal sectional view, with parts broken away and showing the extensible toe portion of the body retracted;

55 Figures 7 is a cross sectional view taken on the line 7—7 of Figure 6, and

Figure 8 is a cross sectional view taken on the line 8—8 of Figure 6.

Referring specifically to the drawings wherein the same reference characters have been used to designate the same parts throughout, numeral 60 2 denotes the surface of a table or other support upon which is mounted the circular base portion 3 of the ironer having the upstanding tubular portion 4 whose upper end supports the stocking like form 5.

65 The portions 4, 5 are secured together by machine screws 6 extending through ears 4^a, 5^a respectively.

The form 5 is hollow and has its end provided with a solid portion 5^b it being observed from 70 Figure 7 that the form 5 is elliptically enlarged as indicated at 5^c.

The toe portion 10 is extensibly connected to the solid end 5^b of the foot portion of the member 5 by means of telescoping rings 7 of sheet 75 metal which are held in assembly by the pin and slot connections 7^b, 7^a. The outer rings are secured to the portions 5, 10 by means of machine screws or other suitable fasteners 8, 9 respectively.

80 Suitable adjustment of the toe portion 10 is effected by means of the rod 12 which is threaded into the tapped hole 10^b in the end wall of the chambered toe portion 10,—such wall being denoted at 10^a. The outer end of the rod 12 has 85 a reduction 12^a providing a shouldered seat for one end of a coil spring conduit 13 within which extends the chain or other flexible connection 14 which is secured at one end to the reduction 12^a and at the other end to the lug or reduction 90 15^a of a second rod 15. The coil spring conduit has its other end disposed about the reduction 15^a and abutting the end of rod 15.

As clearly shown in Figures 1 and 6 the rods 12, 15 and the coil spring conduit 16 work in 95 a tubular conduit having one end threaded into the solid end 5^b of member 5 and the other end carried by a partition 17 soldered or otherwise rigidly secured in the member 5 at its lower end. The rod 15 extends through the partition 100 17 and has its end threaded as at 15^b into the socket portion of a bearing member 18 whose bifurcated opposite end receives the end of a lever 20 which is pivotally secured thereto as at 19.

105 Lever 20 is pivoted as at 21 to an upstanding carrier member 22 which in turn is pivoted as at 23 to the ear 24 of the base. The pivots 19, 21, 23 enable the lever 20 to be swung freely in a vertical plane to control the position of the 110

toe portion 10 through the rods 12, 15 and the flexible connection 14.

The medial portion of base 3 has a set screw 25 projecting into the tubular portion 4 to limit the downward movement of the lever 20. A stop sleeve 26 is secured on rod 15 as shown.

Figures 1 and 4 illustrate a novel latch means whereby the lever 20 can be held in a predetermined position, the same comprising a leaf 10 spring 27 secured on the side of lever 20 and having a pin 28 carried by its free end to extend through the lever as indicated in Figure 4 to selectively engage in the arcual series of recesses 29 formed in the adjacent surface of the 15 segmental inwardly projecting portion 22^a of member 22. The end of the pin 28 is preferably beveled so as to ride in and out of the recesses 29 in the manual movement of the lever 20. However, the pin and recess latch 28, 29, will 20 serve to hold the lever stationary against accidental movement.

Manifestly, the flexible coil spring conduit engaging the ends of rods 12, 15 will actuate the toe portion outwardly when the lever is pushed 25 upwardly. It will also be clear that the flexible connection 14 will serve to pull the toe portion inwardly when the inner end of the lever is swung downwardly.

Figure 1 illustrates that the steam or other 30 hot fluid conduit 30 extends upwardly through the base 3, partition 17 and is threaded as at 30^a into the solid end portion 5^b, the opposite side of said portion 5^b receiving a packing gland 32, through which extends the tube 31 which 35 is carried by the end wall 10^a of the toe portion 10. One end of the pipe 31 communicates with the interior of the toe portion 10 while the other end extends a substantial distance into the fluid supply pipe 30. At the opposite 40 side of the rod 12 from the inlet tube or pipe 31 the wall 10^a has a return pipe 33 seated therein as indicated at 33^a. This return pipe 33 extends through the packing gland 35 in portion 5^b and through such portion a substantial 45 distance into the outlet or guide tube 36 whose inner end is threaded into the portion 5^b as indicated at 36^a.

Manifestly, the telescoping inlet and outlet 50 tubes or pipes 30, 31 and 33, 36 permit extension and retraction of the toe portion 10 without breaking the fluid lines. The entire body or 55 form 5 will be heated by the fluid as it passes through the pipes or tubes 30, 33 and by the fluid which is discharged from the short pipe 36.

Figure 3 shows the fluid outlet pipe 37 having the connecting line 38 extending downwardly through the base 3 for return to the boiler or to a suitable point of exhaust.

The practical operation of the device will 60 doubtless be readily apparent to those skilled in the art from the foregoing description read in connection with the accompanying drawings. A stocking to be dried or ironed is placed upon 65 the form 5 with the toe portion 10 of the form retracted as in Figure 6. After the stocking is in place the lever 20 is actuated to extend the toe portion 10 to fill out the foot of the stocking. The steam is then turned on and the stocking 70 allowed to remain on the form until dry. When the stocking is dry the toe portion 10 is retracted to the position shown in Figure 6 and the stocking is grasped by the vacated toe thereof and pulled off of the form.

The device is made in all manner of sizes

and shapes and while primarily intended for the drying of men's, women's and children's hosiery, it may be used for other garments as well.

Having thus described my invention what I claim as new and desire to secure by Letters 80 Patent is:

1. A garment drying device comprising an extensibly connected pair of body portions, each of said body portions providing a chamber and being closed at their adjacent ends, actuating means secured to said body portions, telescoping conduits connecting the chambers of said body portions and means for supplying a heating fluid to one of said conduits.

2. A garment drying device comprising an extensibly connected pair of body portions, each of said body portions providing a chamber and being closed at their adjacent ends, actuating means secured to said body portions, telescoping conduits connecting the chambers of said body portions, means for supplying a heating fluid to one of said conduits, and said body portions having telescoping extensions adjacent their meeting ends and connected to one another.

3. The combination set forth in claim 1 and swingable control means carried by one of said sections and connected to said actuating means.

4. The combination set forth in claim 1, and including swingable control means carried by 105 one of said sections, said control means being connected to said actuating means, and a swingable mounting for said control means.

5. The combination set forth in claim 1, and including swingable control means carried by 110 one of said sections, said control means being connected to said actuating means, a swingable mounting for said control means, and latch means associated with said swingable control means and its mounting whereby such control 115 means may be maintained in a predetermined position.

6. A device of the class described comprising a base an upstanding tubular portion carried by said base, a chambered form secured to said 120 upstanding tubular portion and communicating therewith, said form being closed at its opposite end from said tubular portion, a chambered form element having a telescoping connection with said first mentioned chambered form, a 125 heating fluid supply conduit extending through said base and secured in the closed end of said first mentioned form, a supply tube carried by said second mentioned form and having a telescoping connection with said fluid supply conduit, a control rod carried by said second mentioned form and extending through the end of said first mentioned form, a guide sleeve carried by said last mentioned end of the first form and into which said control rod extends, a sec- 130 ond control rod carried by said first form adjacent the tubular base portion, a partition in said first form adjacent said tubular base portion and carrying said last mentioned control rod and the other end of said guide sleeve, the 135 inner ends of said control rods having reductions providing shoulders, a flexible connection secured to the reductions of said control rods, a coil spring conduit surrounding said control rod reductions and bearing against said shoulders, 140 an upstanding mounting at one side of said base, and pivoted thereto, a lever pivoted to said mounting and having an operative connection with said second control rod, a stop on said 145 control rod and adapted to engage said parti- 150

tion whereby to limit outward movement of said second form portion, telescoping sleeve extensions connecting said chambered form portions, and means for holding said lever in a predetermined adjusted position.

7. A garment drying device comprising a chambered body portion, a chambered end portion, telescopic rings extensibly connecting said body portion to said end portion, closures for 10 said portions at their adjacent ends, means for adjusting the relative position of said end portion, and means for heating said portions.

8. A hosiery drying device comprising a chambered body portion, an end portion extensibly connected to said body portion by telescopic rings, means for adjusting the relative position of said end portion, means for limiting the movement of said adjusting means, means for supplying a heating fluid to said portions, and extensible telescopic heat supply means connecting said portions.
